UNITED STATES PATENT OFFICE.

N. HOAG AND WM. H. TAPPEY, OF PETERSBURG, VIRGINIA.

IMPROVEMENT IN TOBACCO-SCREWS.

Specification forming part of Letters Patent No. **27,631**, dated March 27, 1860.

To all whom it may concern:

Be it known that we, N. HOAG and W. H. TAPPEY, of the city of Petersburg, county of Dinwiddie, and State of Virginia, have invented a new and useful Improvement on a Tobacco-Screw; and we do hereby declare that the following is a full, clear, and exact description of the construction and operation of the same, reference being had to the annexed drawings, making a part of this specification, in which—

Figure A is a horizontal section of the top-plate. Fig. B is a horizontal section of the under plate. Fig. C is a vertical section of A and B connected.

Similar letters of reference indicate corresponding parts in the three figures.

Our invention consists in the construction of two plates with slats and key for the purpose of supporting a heavy lever in tobacco-press screws.

D represents the body of the screw, with the plates A fitted loose and the plate B keyed tight thereon.

E represents six slots or openings, as shown in Fig. B, in which a key, F, rises and falls alternately as the lever G, with plate A, moves

backward and forward. By reversing the key F the motion of the screw will likewise be changed, so as to move up or down.

H is a turned disk in Fig. B, raised for plate A to work thereon. The backward motion of plate A causes key F to rise by means of the bevel point I, and consequently drops into each succeeding slot or opening.

The operation will be readily understood. By turning plate A by means of lever G the key F will alternately move up and down, and cause plate B, with screw D, to be operated as desired.

The above implement is extremely cheap, simple, and works well.

Having thus described our invention, what we claim as new, and desire to secure by Letters Patent, is—

The arrangement of the several parts combined as constituting the specific machine, for the purpose shown and set forth.

N. HOAG.
W. H. TAPPEY.
